CONVEYER SLAT

Otis C. Currie, Jackson, Mich., assignor to
 Reynolds Spring Company, Jackson, Mich., a
 corporation of Delaware

Application May 27, 1938, Serial No. 210,491

6 Claims. (Cl. 198—199)

The present invention relates to improvements in conveyer slat construction.

Heretofore it has been the general practice, particularly in farm implements, to fabricate the slats of conveyers used in threshers and harvesters from hickory wood. In service such slats warp and are easily broken. However, they are light weight and inexpensive to manufacture, so notwithstanding these inherent difficulties they have continued to be extensively used up to the present time.

I have recently been successful in providing a rolled metal slat for conveyers which has been approved and is now being used by manufacturers of farm machinery. It is to be understood that the slat construction herein disclosed is equally useful in other fields employing conveyers.

According to the present invention I provide a light, rigid and inexpensive slat by rolling a continuous metal strip into the desired shape, cutting the continuous strip into lengths and then shaping opposite ends of each slat so as to permit convenient mounting thereof upon chain links.

Thus, one of the objects of the present invention is to provide a rolled slat of light gauge metal which is rigid in section and has a longitudinally extending reinforcing rib.

Another object is to provide a rolled metal slat of tubular section having an upright face and an inclined reinforcing face functioning as a truss for said upright face.

A further object is to provide a tubular slat having flattened ends for attachment to chain links.

These and other objects residing in the invention as to combination, arrangement and construction of parts will more fully appear in the following description when considered in connection with the accompanying drawing and the annexed claims.

In the drawing,

Fig. 1 is a perspective view of a chain and scraper conveyer embodying the present invention,

Fig. 2 is a perspective view of the improved slat mounted upon chain links,

Fig. 3 is a cross-sectional view taken on line III—III of Fig. 2,

Fig. 4 is a fragmentary plan view of one end of the slat, and

Fig. 5 is an end view of Fig. 4.

Referring to the drawing, in Fig. 1 the present invention is illustrated in connection with a chain and scraper type of conveyer, comprising chains 10 and 12 running over sprockets 14 and 16.

Carried by the chains 10 and 12 are slats 18 functioning as scrapers to convey material along the surface 20. The conveyer illustrated is one used in harvesting and threshing combines for elevating the cut grain and forms no part of the present invention except insofar as it relates to the specific construction of the slats 18. My improved slat may be used in various kinds of conveyers and is not necessarily limited to the so-called "scraper" type.

As more clearly shown in Figs. 2 to 5, inclusive, the slat 18 is of tubular construction, being substantially triangular in cross-section and having an upper stiffening rib 20. For convenience of description the vertically inclined and horizontal sides of the slat 18 have been identified by reference characters 22, 24 and 26, respectively. In practice, the slat 18 is preferably fabricated of relatively light gauge sheet metal, twenty gauge material being found satisfactory in most cases. The tubular section from which the slats 18 are cut is formed in a rolling machine to the cross-section shown in Fig. 3, with the rib 20 formed by overlapping a portion of the side 18 upon the top edge of the side 24. The 3-ply metal making up the rib 20, together with the spot welding of the same at 28, gives a great deal of rigidity to the otherwise inherently rigid triangular section of the slat. In Fig. 2 the ends 30 and 32 of the slat 18 are shown flattened to provide a double ply portion at opposite ends having holes 34 to receive rivets 36 for riveting the slat to the chain links 38 and 40. In the manufacture of the slats 18 the same are cut to length from a continuous tubular section corresponding to that of Fig. 3 and are then placed in a suitable press to flatten the ends to the shape shown in Figs. 2, 4 and 5. It will be noted from Fig. 5 that the flattened portion 30 is just below the plane of the rib 20 and that the bottom 26 is considerably lower so as to assure that the bottom 26 will have intimate relation with the surface 20 over which it is conveyed by the chains 10 and 12.

It should be apparent to those skilled in the art that the section shown in Fig. 3 will be advanced by the chains, with the vertical wall functioning to push or scrape material being conveyed. Due to the sloping effect of the side 24 and the absence of any depressions or resistance, the slat 18 is substantially self-cleaning, and there will be no accumulation of the material being conveyed. As the load is adjacent the face 22, the stiffening rib 20 will resist any deflection of the side 22, while the inclined side 24 will function as a truss

to support the wall 22 in its vertical position against the pressure of the load. The flattening of the ends 30 and 32 in the manner shown likewise tends to stiffen the slat 18. All these factors have been coordinated in my improved slat construction and have made it possible to fabricate a light weight inexpensive slat possessing the rigidity required for satisfactory use.

Having thus described my invention, what I claim as new and desire to secure by Letters Patent is:

1. A conveyer slat of the type described, comprising a sheet metal substantially triangular tubular section having two sides thereof overlapping and forming a longitudinally extending, outwardly projecting stiffening rib, one of said sides having a reversely bent portion in folded relation with the other of said sides, one of the sides of said section being flat and comprising the working face thereof.

2. A tubular conveyer slat comprising a strip of relatively light gauge sheet metal arranged in the form of a tube, the longitudinal edge portions of said strip being in overlapping relation providing a longitudinally extending, outwardly projecting reinforcing ridge, one of said edge portions having a reversely bent portion in folded relation to the other of said edge portions.

3. A rigid light weight conveyer slat comprising a single sheet of sheet metal arranged in the form of a tube, the longitudinal edge portions being folded upon one another and welded together forming an outwardly projecting longitudinally extending stiffening rib, one of said edge

portions having a reversely bent portion in folded relation to the other of said edge portions, the ends of the tubular section being flattened to bring opposed portions of the tube into metal to metal contact with each other.

4. A rigid conveyer slat formed from a continuous piece of light gauge metal by being rolled into a tube, said tube being of substantially triangular cross-section with the longitudinal edge portions of sheet metal being connected to each other to provide an upper longitudinally extending reinforcing rib, the opposite ends of said slat being flattened to dispose the end portions of said tube in metal to metal contact in the plane below said rib and materially above the bottom portion of said tubular section.

5. A conveyer slat of the type described, comprising a rigid tubular member of light gauge sheet metal having vertical and horizontal faces, and an inclined face supporting the vertical face in the direction of the applied load, said inclined face and vertical faces having their respective upper edges folded together into a reinforcing ridge, said ridge constituting an extension of said vertical face.

6. A rigid light weight conveyer slat comprising a single sheet of sheet metal arranged in the form of a tube, the longitudinal edge portions being folded upon one another and connected together, the ends of said tubular section being flattened to bring opposed portions of the tube into metal to metal contact with each other.

OTIS C. CURRIE.
